COMBINATION PAPER DRIER INSTALLATION

Filed Jan. 29, 1927

UNITED STATES PATENT OFFICE.

JOHN E. ALEXANDER, OF PORT EDWARDS, WISCONSIN.

COMBINATION PAPER-DRIER INSTALLATION.

Application filed January 29, 1927. Serial No. 164,401.

This invention relates to a combination paper drier installation and more particularly to a combination of steam heated drum driers of the common type used in paper machines with an electrically heated drier unit adapted to supply steam generated from the drying of paper thereon for utilization in the drum drier.

In the drying of paper electrically as disclosed in my Patent, No. 1,330,366, which is sued February 10, 1920, the steam generated from the moisture in the paper is available for use for heating and power purposes, due to the fact that the electric drier unit is completely housed so as to prevent the admission of substantial quantities of air. I now propose to utilize the steam so generated in the electrical drier unit in steam drier drums of standard type and also to provide a gradient heating system. By this arrangement, not only is the economy of the electrical drier unit greatly increased, but there also results certain advantages in the drying of the paper from the fact that the paper may be dried in gradually increasing temperatures.

Other and further important advantages and objects of this invention will become apparent from the following description and the appended claims.

30 On the drawings:

The figure is a diagrammatic elevational view of a combination paper machine drier installation embodying the principle of my invention.

35 As shown on the drawings:

The reference numeral 1 indicates a housing enclosing a series of hollow, steam heated drier drums 2 of standard type. The steam is adapted to be admitted to one group A of said drier drums 2 through a header 3 and branch pipes 4 leading to the journals of said drier drums. In starting up the paper machine, boiler steam or steam from other sources may be introduced into the header 3 through a pipe 5, but after the machine has been in operation for a sufficient length of time the steam utilized in the group of driers A is obtained from an electrical drier unit 6 associated with the steam heated drier drums of standard type, as will later be explained.

A web of paper 7 as it is delivered from a pair of press rolls 8 on the wet end of the machine is transferred from the press felt 9 and introduced between sealing rolls 10 positioned

in the end of the housing 1. Said web of paper 7 is then threaded around the lower and upper drier drums 2 in the group of driers A in the usual fashion. From the group of driers A, the web 7 passes around a certain number of drier drums forming a group B. The web thence passes between sealing rolls 11 in the other end wall of the housing enclosing the electrical unit 6. Within the electrical unit 6 the web 7 travels in superposed horizontal passes 12 between electrical heating units (not shown). The type of electrical drier unit used is preferably that disclosed in my patent above referred to. From the electrical unit 6 the web 7 passes out between the sealing rolls 13 and is delivered to a set of sweat driers 14 from which the web passes to a calender stock 15 and thence to the reels (not shown).

Steam generated within the housing of the electrical unit 6 is carried by means of a header 16 leading off through the top wall of said casing by means of branch pipes 17 and 18 to the drum driers in group B. The steam enters the driers in group B through pipes 19 and is exhausted through pipes 20 into a lower offset portion 21 of the steam header 3. The exhaust steam from the drum driers in group B then passes through header 3 and branch pipes 4 into the drum driers in group A, the exhaust and condensate from said driers passing through pipes 22 into a lower drain header 23. Said drain header 23 is preferably connected through a pipe 24 to a source of vacuum (not shown).

For the sake of better heat economy, the casing 1 is provided at the top with an exhaust conduit 25 for carrying away the heated vapors and air from inside the casing 1 and an economizer 26 is provided in the exhaust line 25. The economizer 26 may be of any suitable type, wherein incoming air to the casing 1 is heated by the outgoing vapors and air passing out through the conduit 25.

In starting up the machine, as pointed out above, steam from other sources than the electrical drier unit 6 must be introduced into the steam header 3 and the drier drums 2 in order to secure initial drying of the paper. After the paper web has been passing through the drying system for a sufficient length of time, however, the steam generated in the electrical unit 6 from the moisture in the paper may be utilized directly in the drier drums 2, either

- partly or wholly to supplant the steam from other sources. It should be noted that all of the steam from the electrical drier unit 6 passes first through the drum driers in group 5 B, thereby insuring a higher temperature of these driers than will be reached in the case of the drum driers in group A. As is well known, for satisfactory drying the paper, it is best to start the wet web of paper over the 10 drier drums at a moderate temperature in order to prevent searing the paper and trapping the moisture therein. The temperature in the electrical drier unit 6 may, of course, be controlled within any desired limits, under 15 the principles and means disclosed in my patent referred to above. The sweat driers 14 serve the usual purpose of permitting the web of paper to regain some of its normal moisture content.
- 20 It will be apparent to those skilled in the art that a combination of drum driers and electrical drier unit as described will have other advantages besides those of an economical nature. These will manifest themselves, in 25 part, in improved quality of paper due to better control of the temperature in the driers, and in part to the other conditions under which the paper is dried. For instance, in 30 drying paper on drum driers, there is a tendency, due to the fact that the drier felt holds the web of paper tightly against the surface of the drum, for the paper to lose some of the strength that it would have were it free to contract naturally. In the electrical drier 35 unit however, the web of paper can dry more freely and retain a large measure of its natural tensile strength. On the other hand, if an electrical drier unit were used alone, the 40 paper would not present such a good surface appearance as where the paper has passed over steam heated drier drums. The combination of the electrical drier unit with the steam heated driers therefore possesses the 45 advantages of each type.
- 50 My invention also contemplates the installation of an electrical drier unit in conjunction with present paper machine installation having steam drum driers of the usual type. In such a case, it would merely be necessary to lengthen the machine in order to set up the electrical drier unit between the present drum driers and the calender stack.
- 55 While for the sake of heat economies, the steam drum driers should be enclosed and a steam economizer used in connection with the exhaust from the enclosure, it will be understood that these points are not essential to my invention. Furthermore, the drum driers may be piped in various ways to receive the 60 steam from the electrical drier unit, and they may be in vertical tiers as well as horizontal.
- 65 I am aware that many changes may be made, and numerous details of construction may be varied through a wide range without departing from the principles of this inven-

tion, and I therefore do not propose limiting the patent granted hereon, otherwise than necessitated by the prior art.

I claim as my invention:

1. In a drier installation, the combination 70 with an electrical drier unit adapted to generate steam from the moisture in the material to be dried, of drier drums for receiving the steam so generated and utilizing the heat therefrom in the drying of said material. 75
2. In a paper drier installation, an enclosed electrical drier unit through which the web of paper is adapted to be passed to be dried, a plurality of drum driers operatively associated therewith and means for conducting 80 steam generated within the electrical drier unit from the moisture in the paper web to said drum driers.
3. In a paper drier installation, a closed 85 housing, an electrical drier unit therein for drying the paper, a plurality of drum driers arranged ahead of said electrical drier unit for effecting partial drying of the paper and means for conducting steam electrically generated within said housing from the moisture 90 in said paper to said drum driers for heating the latter. 95
4. A combined paper drier installation, comprising a plurality of steam heated drum driers and an electrical drier unit, the web 100 of paper being adapted to pass successively over said drum driers and through said electrical drier unit and means connecting said electrical drier unit and said drier drum for utilizing in said drier drums steam generated in said electrical drier unit from the moisture 105 in said paper, said drier drums being divided into groups for receiving all of the steam through one of said groups first. 110
5. In a drier system, the combination with 115 a plurality of drier drums, of an auxiliary drier unit, heating means therein for transforming a part of the water in said web into steam, and means for conducting said steam into and through said drums to heat the same. 120
6. In a drier system, the combination with 125 a plurality of drier drums, of an auxiliary drier unit, high-temperature heating means therein for transforming a part of the fluid in said web into dry superheated vapor, and means for conducting said vapor into said drums to heat the same. 130
7. In a drier system, the combination with 135 a plurality of drums for operatively engaging a web of material to dry the same, of an auxiliary drier unit for effecting a partial drying of said web, high temperature heating means in said drier unit for transforming the water in said web into dry superheated steam, and means for conducting the steam from the auxiliary drier unit into and through said drums to heat the same. 140
8. In a drier system, the combination with 145 a plurality of rotatable drums for operatively engaging a web of material to be dried, of an

auxiliary, substantially enclosed, drier casing located in the path of said web, high temperature electric heating means in said casing for transforming a portion of the water 5 in said web into dry superheated steam, and means for conducting said steam into and through said drums to heat the same.

9. In a drier system, the combination with a plurality of rotatable drums for operatively 10 engaging an initially wet web of material to be dried, of an auxiliary drier casing, means for moving said web through said drier casing, means in said drier casing for transforming a part of the water in said web into dry 15 superheated steam, and means for conduct-

ing the steam into said drums to heat the same and to dry the web.

10. In a drier system, in combination, a substantially enclosed drier casing, means for moving an initially wet web of material 20 through said casing, a plurality of rotatable drums for operatively engaging said web of material, heating means in said casing for transforming a part of the water in said web into dry superheated steam, and means for 25 conducting said steam into and through said drums to heat the same.

In testimony whereof I have hereunto subscribed my name.

JOHN E. ALEXANDER.
